UNITED STATES PATENT OFFICE.

CHARLES W. SCHEESLEY, OF JERSEY SHORE, PENNSYLVANIA, ASSIGNOR TO SUSQUEHANNA SILK MILLS, OF NEW YORK, N. Y., A CORPORATION OF NEW YORK.

ADJUSTABLE TENSION DEVICE.

Application filed October 3, 1921. Serial No. 505,053.

To all whom it may concern:

Be it known that I, CHARLES W. SCHEESLEY, a citizen of the United States, residing at Jersey Shore, in the county of Lycoming and State of Pennsylvania, have invented certain new and useful Improvements in Adjustable Tension Devices, of which the following is a specification, reference being had therein to the accompanying drawings.

This invention relates to an adjustable tension device for use in shuttles, and the object of the invention is the construction of a simple and efficient tension device for automatic shuttles, whereby the thread for the shuttle will fall into both the threading block and the tension device as soon as the pick of the shuttle is started.

Another object of the invention is the construction of a tension device for shuttles, which can be easily manipulated for causing the clamping elements or jaws to be adjusted for controlling the pressure and distance between the two contiguous faces of the jaws, at the will of the operator.

With the foregoing and other objects in view, my invention comprises certain novel combinations, constructions and arrangements of parts as will be hereinafter described, illustrated in the accompanying drawings, and more particularly pointed out in the appended claims.

In the drawing:

Figure 1 is a fragmentary, perspective view of a shuttle-body, showing my improved device mounted therein.

Figure 2 is a fragmentary view, in side elevation, of the shuttle-body.

Figure 3 is a sectional view, taken on line 3-3, Fig. 4, and looking in the direction of the arrows.

Figure 4 is a sectional view, taken on line 4-4, Fig. 3, and looking in the direction of the arrows.

Figure 5 is a perspective view of the sliding washer of the device.

Figure 6 is a fragmentary, bottom view of the threading block, showing my device mounted therein.

Referring to the drawings by numerals, 1 designates the shuttle-body, 2 the threading block, and 3 the bobbin. In Fig. 1, the thread or filling 4 is shown passing into my tension device and the threading block.

The preferred form of my tension device,

shown in the drawings, comprises a primary jaw 5, and an auxiliary jaw 6. These jaws 5 and 6 are positioned in a compartment or pocket 7 formed in the threading block 2. The primary jaw 5 has some "play" 60 or sidewise movement in the compartment 7. The auxiliary jaw 6 is provided with an upper, curved end 8, so that the thread or filling falling down the slot 9, of the threading block 2 (Fig. 3) will be readily 65 directed between jaws 5 and 6. Extending through the threading block 2 is a rotatable member or screw 10; this screw 10 extends through the two jaws 5 and 6 and is threaded into the sliding washer 11. The washer 11 70 is provided with a depending lug 12, which lug 12 slides in a groove 13 formed in the threading block. The groove 13 prevents the washer from rotating, and allows the screw 10 to be threaded into the washer, 75 which will cause the washer to ride or slide inwardly compressing the coil spring 14, thereby adjusting the auxiliary jaw 6, depending upon the rotation of screw 10. In Fig. 6, the washer 11 is shown partly extending into compartment 7, whereas in Fig. 3, the washer is at the innermost position upon screw 10. This Fig. 6 illustrates the positioning of the washer 11 toward the auxiliary jaw 6 by the rotation of 80 the screw 10.

I have found from practical experience that the "tension" of the device can be quickly and easily adjusted to obtain great accuracy, and the device can be adjusted 90 through the medium of screw 10, to accommodate different fillings or threads, as the case may be.

It is to be understood that the jaws are operated by the screw principally for controlling the pressure on the thread, and, incidentally, for adjusting the distance between the two jaws, since pressure will only be exerted on the filling when the distance between the jaws is restricted according to 100 the size of the thread or filling.

In the foregoing description, I have designated 5 and 6 as "jaws", but I do not limit these elements to any specific term, for the word "jaws" is used in a broad sense, meaning "jaws", "blocks", or thread or filling "engaging elements", or the like.

While I have described the preferred embodiment of my invention, and have illustrated the same in the accompanying draw- 110

ings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. In a device of the class described, the combination with a threading block, of a screw extending across said threading block, jaws loosely mounted on said screw, a washer on said threading block and threaded upon the screw, said washer and threading block provided with means for preventing rotation of the washer, and a coil spring interposed between said washer and one of the jaws and mounted on the screw.
2. In a device of the class described, the combination with a threading block, of a screw extending across said threading block, a washer threaded upon one end of said screw and adapted to slide transversely of the threading block, means for preventing rotary movement of the washer, a pair of jaws on said screw, and a spring pressing at one end against the washer and at its other end against one of the jaws.
3. In a device of the class described, the combination of a threading block provided with a compartment and a groove, a screw extending across said threading block and having a portion above said groove, a washer threaded on said screw and provided with a lug, said lug positioned in said groove of the threading block, jaws engaging said screw, and a spring between the washer and one of the jaws, whereby when the screw is rotated the washer will be caused to move along the screw for controlling pressure on the spring.
4. In a device of the character described, the combination of a threading block having a slot extending thereinto and communicating with an internal compartment, a rotatable screw carried by said threading block and extending transversely through said compartment, a flat vertically extending primary

jaw loosely mounted upon said screw within said compartment, said primary jaw extending to one side of said slot, a flat vertically extending auxiliary jaw loosely mounted upon said screw within said compartment, the body portion of the auxiliary jaw extending contiguous to the primary jaw, said primary jaw having a curved upper end 55 projecting away from the primary jaw and below said slot, whereby thread falling down the slot will readily fall between the jaws, and a compression means carried upon the inner end of the screw to bear upon said auxiliary jaw, as and for the purposes set forth.

5. In a device of the character described, the combination of a threading block having a slot extending thereinto and communicating with an internal compartment, a rotatable screw carried by said threading block and extending transversely through said compartment, a flat vertically extending primary jaw loosely mounted upon said screw within 60 said compartment, said primary jaw extending to one side of said slot, a flat vertically extending auxiliary jaw loosely mounted upon said screw within said compartment, the body portion of the auxiliary jaw extending contiguous to the primary jaw, said primary jaw having a curved upper end 65 projecting away from the primary jaw and below said slot, whereby thread falling down the slot will readily fall between the jaws, a washer threaded upon the inner end of said screw and slidable transversely of said threading block, said threading block having a transverse groove communicating with said compartment, said washer having a lug 70 extending into said groove, thereby keying said washer upon said threading block, a coil spring carried upon said screw and being interposed between said washer and said auxiliary jaw, as and for the purposes set 75 forth.

In testimony whereof I hereunto affix my signature.

CHARLES W. SCHEESLEY.
